BASE FOR HIGHWAY FLARES

George J. J. Clark, Whitman, Mass., assignor to
National Fireworks, Inc., West Hanover, Mass.,
a corporation of Massachusetts

Application October 24, 1935, Serial No. 46,509

4 Claims. (Cl. 248—46)

This invention relates to improvements in bases for highway flares, and the object thereof is to provide a simple and convenient device which can be placed upon a concrete or macadam road-bed and which will effectively support a flare, such as a fusee, in proper position to burn readily and which will prevent guttering of the casting of the flare.

Laws have been passed in certain States and 10 municipalities requiring public conveyances, such as bus companies, truck lines, etc., to equip their vehicles with flares, such as railroad fusees, or the like, which must be lighted when the vehicle is stopped enroute for the purpose of making 15 repairs, changing tires, etc., to safeguard the vehicle against collision while it is stopped. Inasmuch as the greater part of the road-bed over which such vehicles operate are of concrete or macadam construction it is impossible to embed the spike of a usual railroad fusee into the road-bed at a proper position to provide a signal, or to 20 enable light from the burning flare to give proper illumination to the part of the vehicle which is being repaired.

More specifically the object of the invention is 25 to provide a base for a highway flare so constructed that it can be readily collapsed and stored in a relatively small space and which when expanded can be placed upon the road-bed to support the flare in a proper manner to enable it to 30 burn throughout its length without hindrance and without guttering.

A preferred embodiment of the invention is ill- 35 lustrated in the accompanying drawing, in which,

Fig. 1 is a perspective view of a base for highway flares in extended position showing the flare supported thereby in dotted lines;

Fig. 2 is an enlarged side elevation of the construction shown in Fig. 1 partially broken away showing the flare in collapsed position;

Fig. 3 is an underneath plan view of the device shown in Fig. 1 illustrating the foot members of the device in divergent position, the foot members and flare being partially broken away; and,

Fig. 4 is an underneath plan view of the socket member showing in dotted lines the foot members in extended positions and particularly illustrating a stop lug adapted to limit the movement of the foot members to either extended position or superimposed position.

The base for highway flares illustrated in the accompanying drawing comprises a flare-holding socket having a flat bottom 1 and flare-supporting means extending upwardly in angularly in-

clined relation to said bottom. The flare-supporting means preferably comprises a tubular wall 2 integral with and extending upwardly from the base member 1 in axially inclined relation thereto. The socket preferably is of cylindrical form adapted to receive a flare 3, such as a railway signal fusee, having no spike at its lower end, or other suitable pyrotechnical device. The under side of the bottom 1 desirably is provided with a channel 4 having vertical walls 5 and 6 and a flat metallic bar 7, preferably of a thickness equal to the height of the walls 5 and 6 of the channel, fits in said channel and extends therethrough to provide long and narrow foot sections 8 and 9.

Another complementary foot member, preferably in the form of a flat metal bar 10, is pivotally secured to the bottom 1 by a rivet 11 which extends through the bottom and also through the stationary foot member 7 and the movable foot member 10. The foot member 10 desirably is of the same length as the foot member 7 and has sections 12 and 13 extending from said pivot distances respectively equal to the length of the sections 8 and 9 of the member 7.

By reason of this construction the foot members 7 and 10 may be spread to diverging positions, as illustrated in Fig. 1, or folded to a position in which the movable foot member 10 will underlie the foot member 7, thereby placing them in superimposed or collapsed position in which the device can be readily stored in a relatively small space.

The channel 4 is disposed in such angular relation to the vertical plane X—X Fig. 3 of the inclined axis of the tubular flare-supporting socket that when the foot members are in divergent positions the foot members will diverge at substantially equal and symmetrical angles from the vertical plane of the inclined axis of the socket, so that the flare will be supported substantially centrally of the angular area between the longer foot sections when in extended position, illustrated in Fig. 1.

Desirably means are provided for limiting the relative movement of the foot members to such position that the flare will be thus supported substantially centrally of the area between the long sections of the diverging foot members. This is conveniently accomplished by providing the base with a downwardly extending lug 14 having a vertical shoulder 15 adapted to be engaged by an edge of the pivotally mounted foot member when in extended or divergent position, as illustrated in Figs. 1, 3, and 4. Said lug desirably is

also provided with a shoulder 16 adapted to be engaged by the same edge of the movable foot member when in collapsed position.

While the preferred flare socket illustrated in the accompanying drawing is in the form of an integral tubular socket having a cylindrical wall axially inclined to its bottom, it is to be understood that the socket may be of skeletonized or of any other desirable form properly to receive the bottom of the flare. It will also be understood that other means may be provided for limiting the relative movement of the foot members, such as by a projection or projections extending from one of the foot members adapted to engage the other when proper angular relation of the foot members is assumed or when the members are superimposed as aforesaid.

It will therefore be understood that the particular embodiment of the invention shown herein is of an illustrative character and is not restrictive of the meaning and scope of the following claims.

Having thus described the invention, what is claimed as new, and desired to be secured by Letters Patent, is:

1. A base for highway flares comprising a flare-holding socket having a bottom and an integral tubular wall extending upwardly in angular inclined axial relation to said bottom, said bottom being provided on its under side with a channel, a stationary narrow flat foot member of substantial length extending through said channel, a second flat foot member of substantial length secured to said bottom by a pivot extending from said bottom through both of said foot members, whereby said relatively movable foot members may be folded into superimposed position or divergently spread in such manner that a flare inserted in said socket will be held in inclined position over the angular area between said diverging foot members.

2. A base for highway flares comprising a flare-holding socket having a bottom and an integral tubular wall extending upwardly in angular inclined axial relation to said bottom, said bottom being provided on its under side with a channel extending in a predetermined angular relation to the vertical plane of the axis of said socket, a stationary narrow flat foot member of substantial length extending through said channel, a second flat foot member of substantial length secured to said bottom by a pivot extending from said bottom through both of said foot members, whereby said relatively movable foot members may be folded into superimposed position or divergently spread in such manner that a flare inserted in said socket will be held in inclined position over the angular area between

said diverging foot members, and means for limiting the movement of said movable foot member to a position in which its angular divergence from the vertical plane of the inclined axis of said socket will be substantially symmetrical to that of the other foot member. 5

3. A base for highway flares comprising a flare-holding socket having a bottom and an integral tubular wall extending upwardly in angular inclined axial relation to said bottom, said bottom being provided on its under side with a channel extending in a predetermined angular relation to the vertical plane of the axis of said socket, a stationary narrow flat foot member of substantial length extending through said channel, a similar flat foot member of substantial length secured to said bottom by a pivot extending from said bottom through both of said foot members, whereby said relatively movable foot members may be folded into superimposed position or divergently spread in such manner that a flare inserted in said socket will be held in inclined position over the angular area between said diverging foot members, and a lug projecting from said bottom limiting the diverging movement of said movable foot member to a position in which its angular divergence from the vertical plane of the axis of said inclined socket will be substantially symmetrical to the angular divergence of the other foot member therefrom. 20 25

4. A base for highway flares comprising a flare-holding socket having a bottom and an integral tubular wall extending upwardly in angular inclined axial relation to said bottom, said bottom being provided on its under side with a channel extending in a predetermined angular relation to the vertical plane of the axis of said socket, a stationary narrow flat foot member of substantial length extending through said channel, a similar flat foot member of substantial length 30 secured to said bottom by a pivot extending from said bottom through both of said foot members, whereby said movable foot members may be folded into superimposed position or divergently spread in such manner that a flare inserted in 35 said socket will be held in inclined position over the angular area between said diverging foot members, and a lug projecting from said bottom limiting the diverging movement of said movable foot member to a position in which its angular divergence from the vertical plane of the axis of said inclined socket will be substantially symmetrical to the angular divergence of the other foot member therefrom, and also limiting the closing movement of said movable foot member to a position in which it is superimposed over the stationary foot member. 40 45 50 55
